Primary Examiner — Mary Ann Calabrese*Assistant Examiner* — Catherine Ho(74) Attorney, Agent, or Firm — Rosenberg, Klein & Lee(57) CLAIM

The ornamental design for a square table, as shown and described.

DESCRIPTION

FIG. 1 is a front perspective view of a square table, showing my new design;

FIG. 2 is a front elevational view thereof, the rear side elevational view being a mirror image thereof;

FIG. 3 is a bottom plan view thereof;

FIG. 4 is a top plan view thereof; and,

FIG. 5 is a right elevation view thereof, the left elevational view being a mirror image thereof.

The broken line portion of the figure drawings is included to show environmental structure that forms no part of the claimed design.
